UNITED STATES PATENT OFFICE.

LAURIE S. MACDONALD AND JOSEPH E. SMALL, OF BROCKTON, MASSACHUSETTS, AS
SIGNORS TO THOMPSON BROS. SHOE CO., OF BROCKTON, MASSACHUSETTS, A COR-
PORATION OF MASSACHUSETTS.

SHOE.

Application filed October 27, 1925. Serial No. 65,183.

This invention relates to the art of making shoes, and is intended to produce a shoe of novel construction partaking of the character of a welt shoe while at the same time being free from certain defects or objectionable features that are incidental to a welt shoe as heretofore made. For example, in lasting a welt shoe it has been the practice, after the edge portion of the upper has been pulled over the insole, to tack this inturned edge to the insole to hold it while the welt, the upper and the insole lip are being stitched together. Often tacks close to the line of stitching are left un-noticed after the edge of the upper beyond the in-seam is trimmed off, while the lasting tacks around the heel-seat are not removed at all since the inseam and welt do not extend beyond the shank portion. Hence it often happens that lasting tacks work through the insole, causing injury and discomfort to the foot of the wearer. The gathering in or puckering of the upper, where it is turned in around the toe and around the heel, tends to produce unevenness at those points.

Again the practice of channeling deeply into the insole bottom to raise a welt-attaching lip and of stitching the heavy welt strip and upper thereto often results in producing ridges or depressions which appear on the top surface of the insole and frequently the line of the inseam stitching is perceptible both to the eye and to the touch.

The present invention obviates these and other deficiencies by sewing the upper directly to the peripheral face of the inner sole, and thereafter sewing the marginal portion of the outer sole directly to the outwardly turned marginal portion of the upper outside of the first mentioned seam, which may be termed the "inseam", whereby the marginal portion of the upper functions as an integral welt for securely uniting the innersole and the outer sole together. No uneven ridges or hollows result from this mode of construction, and entire freedom from lasting tacks is insured since none are retained in the practice of this method. Moreover, as the upper is sewed directly to the peripheral, or outside, face of the insole it makes such a tight joint with the outside face of the insole as to prevent the leakage of water around the edge of the insole which,

of course, can readily occur where a crack is left between the peripheral face of the insole and the adjacent part of the upper.

These and other features of this invention will be described in the following specification and will be defined in the claim hereto annexed.

In the accompanying drawings we have illustrated the construction of a shoe made in accordance with our improved process, in which:

Figure 1 is a perspective view of the shoe upper and insole as assembled on the last and united together by a row of stitching extending entirely around the periphery of the insole.

Figure 2 is a cross sectional view through the forepart of the complete shoe showing how the marginal portion of the upper is employed to firmly unite both the insole and the outer sole.

Figure 3 is a cross sectional view of the inner sole used in this process.

Figure 4 is a bottom plan view of the insole provided with the inseam groove.

Figure 5 is a detail view showing the construction of a shoe bottom having a single outer sole without an intermediate filling layer.

In the practice of this invention, according to the illustration of the drawings, we prefer to employ the inner sole 1, of any usual or desired contour and somewhat thicker than the insoles generally employed for welt shoes. Instead of the usual deep channeling to raise a welt-attaching lip on the bottom of the insole, we cut a very shallow, narrow groove just sufficient to contain the inseam stitches which unite the insole and the upper together.

This insole is secured to the bottom of the last in the usual way, and the upper 2, with or without the usual lining 3, is drawn over the last and the edge of the insole on the last in the usual manner, except that the heel portion of the upper is wiped over the periphery of the heel portion of the inner sole to draw it snugly around the inner sole edge, but no lasting tacks are used to secure the marginal portion of the upper to the inner sole. The pattern for the upper may be cut slightly larger than for an ordinary welt shoe to provide ample margin beyond

the insole to serve as the integral attaching welt for uniting the inner sole and the outer sole together.

The upper is then stitched directly to the peripheral face of the inner sole by a row of stitches 4, which pass through or penetrate the peripheral face of the inner sole 1, as well as through the surrounding or contacting portion of the upper, the seams penetrating as far as the inseam groove 1^a.

If a toe-cap as shown at 5, and a stiffening counter as shown at 6, are used, which is ordinarily the case, they are, of course, interposed between the lining and the upper in the usual manner, and the inseam stitching 4 passes through them as well as through the upper and the peripheral face of the inner sole.

The lining 3, when used, preferably terminates flush with the exposed face of the inner sole 1, leaving a marginal portion 2^a of the upper which is free to be turned outwardly to receive the outer sole against its inside face.

If desired a filling layer 7, cut out from sheet material, such as sheet cork, or formed of plastic material spread over the bottom of the insole, may be employed.

In Figure 2 we have shown a double outer sole comprising layers 8 and 9 of sole leather or other suitable material applied to the structure above described. In practice the outer sole, whether single or double, suitably dimensioned, is applied to the previously assembled portion of the shoe and its marginal portion is stitched directly to the outwardly extending marginal portion 2^a of the upper by means of a row of stitches 10, which row of stitches will preferably extend around the marginal portion of the heel seat as well as around the other portions of the sole in which respect it differs from the ordinary welt shoe.

It will, therefore, be seen that the entire bottom of the shoe, disregarding the subsequently attached heel, has uniform thickness throughout and is, therefore, perfectly level and free from ridges or hollows that ordinarily produce unevenness in an insole.

The sole layers may, of course, be cemented together and the marginal welt portion 2^a of the upper may also be cemented down to the outer sole.

In Figure 5 we have shown the process applied to a simpler form of shoe, namely, one having no intermediate filling layer and having only a single outer sole. In this case the pattern for the upper 2 may be cut slightly smaller than for the shoe construction, shown in Figure 2, since there is no intermediate filling layer and the single outer sole 12 is stitched to the marginal portion 2^a

by a row of stitching 11 in exactly the same way as previously described. The edge of the marginal portion 2^a of the upper may be trimmed and finished at the same time the outer sole is trimmed and finished so that the shoe has the appearance of a welt shoe, and except for certain objectionable features which are eliminated is, in effect, a welt shoe because the marginal portion of the upper functions precisely like a welt.

It will be understood that when the upper has been stitched against the periphery of the inner sole so as to leave the marginal portion of the upper forming a peripheral skirt beyond or outside of the seam any projecting portions of the box toe-cap 5, or of the stiffening counter 6, or of the lining 3, may be trimmed off flush with the bottom or exposed face of the insole. As the row of stitching 4 just fills the shallow groove 1^a and as the marginal skirt 2^a can be turned outward in the same plane as the bottom or exposed face of the insole, the outer sole will be fully supported, whether an intermediate filling layer of sheet or plastic material is used or not, and the stitches 4 serve as a common means of directly uniting and securing the upper, the lining, the stiffening counter, the box toe-cap and the insole together, since it extends around the entire periphery of the shoe. By using intermediate filling layers 7 of different thicknesses, the inseam 4 may be spaced at different distances from the out-seam 10, while by omitting such intermediate filling layer these two seams are located in very close juxtaposition, giving substantially the appearance of a single seam.

What we claim is:

A shoe embracing in its construction an insole of extra thickness and an upper secured directly to the insole by stitches passing through the entire peripheral face of the insole and the sub-tending portion of the upper, a sheet of cork conforming to the contour of the insole and covering its entire area but inclosed within the upper beyond the insole-attaching stitches, an outer sole dimensioned to provide a marginal extension projecting outwardly around the entire periphery of the shoe, the upper, beyond the insole stitching, having a marginal extension forming means for attaching the peripheral portion of the outsole to the shoe, and a row of stitches uniting the projecting margins of the upper and of the outer sole around the entire periphery of the shoe.

In witness whereof, we have subscribed the above specification.

LAURIE S. MACDONALD.
JOSEPH E. SMALL.
